UNITED STATES PATENT OFFICE.

ALFRED L. SCHELLHAMMER, OF WARREN, PENNSYLVANIA.

FURNACE.

Application filed May 7, 1925. Serial No. 28,659.

The present invention relates to furnaces, and more especially to that class of furnaces or heaters adapted to burn a variety of fuels such, for example, as coal, wood, gas or oil.

An object of the invention is to provide a furnace of this class in which a plurality of fire chambers are provided adapted to burn different kinds of fuel and so arranged as to give a maximum heating efficiency to the entire furnace.

Another object of the invention is to provide a furnace of this class in which the gas fire chamber is so arranged that cold air may be brought into the furnace casing at almost any point and can flow under it, around it, and rise above it.

A further object of the invention is to provide in such a furnace a gas fuel heat radiating drum which communicates with the solid fuel fire chamber in the upper part thereof above its grate and preferably only at a single point.

A still further object of the invention is to provide a furnace in which the burned gases from the gas fuel fire chamber pass into a gas fuel radiating drum, from which they are delivered into the upper part of a solid fuel fire chamber, so that from this point such gases may have the same direction as the burned gases from the solid fuel, and may pass from the upper portion of the solid fuel fire chamber either directly into a flue or from the upper portion of the solid fuel fire chamber around through a heat-radiating drum and thence to said flue, the direction to be taken by such burned gases being subject to manual or other control.

Other objects and advantages of the invention will in part be apparent and in part appear from the following detailed description, taken in connection with the accompanying drawings, which illustrate, by way of example, one preferred embodiment thereof, but which are not to be taken as a definition of the limits of the invention, reference being had to the appended claim for that purpose.

In the drawings:

Fig. 1 is a horizontal section taken through a form of furnace embodying the present invention and taken on the line 1—1 of Fig. 2;

Fig. 2 is a vertical sectional view of the furnace taken on the line 2—2 of Fig. 1;

Fig. 3 is a horizontal section taken on the line 3—3 of Fig. 2;

Fig. 4 is a vertical section taken on the line 4—4 of Fig. 3.

Referring in detail to said drawings, a casing 11 has preferably centrally located therewithin and spaced from the inner walls 60 thereof a cylindrical solid fuel fire chamber 12 provided with any suitable form of grate 13, for burning such fuels as coal or wood, and provided with any suitable form of burner 13' for burning oil or other liquid 65 fuel. The burner 13' is preferably located below the grate 13, as shown in the drawings. As the present invention includes two fire chambers, one preferably used for burning gaseous fuel and the other preferably 70 used for burning coal, wood or oil and similar fuels, the fire chambers will, for convenience, be designated, one as the gaseous fuel fire chamber, for burning gas, and the other as the solid fuel fire chamber, for burning 75 other fuels.

Upper and lower doors 14 and 15 are provided in the casing 11 to afford an entrance to the solid fuel fire chamber above and below said grate, respectively. In the upper 80 portion of the solid fuel fire chamber an opening 16 is provided, which leads through the passage 17 into a radiating drum 18, which is preferably circular in form and surrounds the upper portion of the solid fuel 85 fire chamber 12, being spaced from its wall and the wall of the casing.

Referring particularly to Fig. 1, it will be seen that a baffle 19 is arranged diagonally in the radiating drum 18 from the 90 inner wall to the outer wall thereof, and this baffle is located in front of the passage 17 and extends from the bottom of the radiating drum 18 to the top thereof. On the other side of the baffle 19 and directly opposite to the passage 17 a flue 20 is provided to conduct away burned gases and smoke from the furnace. The baffle 19 is provided with a passage 21 therethrough, in which is located a damper 22 adapted to open or close the passage 21. It will thus be observed that by manipulating the damper 22 the

smoke and burned gases from the solid fuel fire chamber may be directed from the top of said chamber through the drum-connecting passage 17, through the passage 21 in the baffle 19, and directly on out through the flue 20, this being the direction taken, for example, when the furnace is first started in operation, and it is important to have a strong and direct draft. At other times the burned gases and smoke from the solid fuel fire chamber 12 may, by closing the damper 22 and thus closing the passage 21, be directed circularly around through the circular radiating drum 18 and thence out through the flue 20.

In the present embodiment of the invention a gaseous fuel fire chamber 23 is located at one side of the solid fuel fire chamber 12, into which leads a pipe 24 for the purpose of conveying gaseous fuel to the burner 25 located in the fire chamber 23. The casing 11 is provided with a suitable door 26 affording entrance to the fire chamber 23, as shown in Fig. 2.

The gaseous fuel fire chamber 23 is preferably arcuate in form, as shown in Fig. 1, and, as will be seen in Fig. 2, is spaced all around from the floor of the furnace casing, from the bottom of the radiating drum 18, and on its sides from the walls of the casing 11 and the solid fuel fire chamber 12.

At each end of the arcuate gaseous fuel fire chamber 23 an opening is provided and each of these openings is connected by a conduit 27 to an opening formed in the lower portion of the arcuate gaseous fuel radiating drum 28. The radiating drum 28 is preferably arranged higher than the fire chamber 23, and in addition to being spaced from the inner wall of the casing and the outer wall of the solid fuel fire chamber 12, is also spaced from the floor of the casing and from the bottom of the radiating drum 18. The radiating drum 28 is also preferably provided with vertical through pipes 29 open at their tops and bottoms, but having closed side walls for the purpose of assisting in the transfer of heat by radiation and convection.

Near the top of the radiating drum 28 a passage 30 connects said drum with the solid fuel fire chamber 12 near the upper portion thereof and above the level of the grate and any combustible material which may be thereon.

It will be seen that the smoke and burned gases from the gaseous fuel fire chamber 23 are, after passing through the gas radiating drum 28, directed into the upper portion of the solid fuel fire chamber 12 above the fuel level thereof and that these gases thereafter will pass out of the furnace and into the flue along the same path taken by the smoke and burned gases from the solid fuel fire chamber, namely, either through the passage

17 and directly into the flue if the damper 22 is open, or through the passage 17 and around through the radiating drum 18 into the flue on the other side of the baffle if the damper 22 is closed.

Considerable difficulty has been experienced with furnaces adapted to burn different kinds of fuel, but it will be noted that in the present invention the burned gases and smoke from the gaseous fuel are not forced up through a bed of coals or other solid fuel, nor are they passed directly out of the furnace before yielding up their heat, but are passed from the gaseous fuel chamber through a gaseous fuel radiating drum and thence into the upper portion of the solid fuel fire chamber above the grate and above the fuel level thereof and thereafter take the same path as the smoke and burned gases from the solid fuel fire chamber, namely, either through a second radiating drum and thence to the flue or directly into the flue without circling through the second radiating drum.

It will also be seen that the gaseous fuel fire chamber may be located as far above the bottom of the furnace as may be desired so that cold air may be brought into the furnace at almost any point without interfering in any way with the delivery of the smoke and burned gases from said gaseous fuel fire chamber into the solid fuel fire chamber because such delivery takes place at any point above the level of the solid fuel.

It will also be seen that there is preferably only one inlet from the gaseous fuel radiating drum into the solid fuel fire chamber.

In the following claim, the term "solid fuel fire chamber" refers to the chamber in which fuels are burned such as oil, coal or wood.

What is claimed is:

A furnace including a casing, a central cylindrical solid fuel fire chamber within said casing, spaced from the interior walls thereof, and provided with an entrance through said casing, a semicircular auxiliary fire chamber in said casing on one side of said solid fuel fire chamber and having an entrance through said casing, a semicircular auxiliary radiating drum on the other side of said solid fuel fire chamber and communicating at its lower ends with the upper ends of said auxiliary fire chamber, air pipes passing vertically through said radiating drum, the upper portion of said radiating drum communicating with the interior of said solid fuel fire chamber, a circular upper main radiating drum surrounding said solid fuel fire chamber and having an opening communicating therewith at the upper portion thereof, a baffle provided with a damper and extending from the in-

terior wall of said radiating drum to the exterior wall thereof and in front of said solid fuel fire chamber communicating opening and adapted, when said damper is closed, to deflect burned gases from said solid fuel fire chamber circularly through said radiating drum, and a smoke flue communicating with said radiating drum on the other side of said baffle and adapted, when said damper is open, to receive burned 10 gases directly from said solid fuel fire chamber.

In testimony whereof I affix my signature.

ALFRED L. SCHELLHAMMER.
